(57) **CLAIM**

The ornamental design for a pet hair lint remover, as shown and described.

DESCRIPTION

FIG. 1 is a top perspective view of a pet hair lint remover, showing my new design;

FIG. 2 is a bottom perspective view thereof;

FIG. 3 is a front elevation view thereof, the rear elevation view is identical;

FIG. 4 is a left side elevation view thereof, the right side elevation view is identical;

FIG. 5 is an enlarged top plan view thereof;

FIG. 6 is an enlarged bottom plan view thereof;

FIG. 7 is an enlarged partial view of portion 7 in FIG. 1;

FIG. 8 is an enlarged partial view of portion 8 in FIG. 1;

FIG. 9 is an enlarged partial view of portion 9 in FIG. 1;

FIG. 10 is an enlarged partial view of portion 10 in FIG. 1;

FIG. 11 is an enlarged partial view of portion 11 in FIG. 2;

FIG. 12 is an enlarged partial view of portion 12 in FIG. 2;

FIG. 13 is an enlarged partial view of portion 13 in FIG. 2;

FIG. 14 is an enlarged partial view of portion 14 in FIG. 2;

FIG. 15 is an enlarged partial view of portion 15 in FIG. 3;

FIG. 16 is an enlarged partial view of portion 16 in FIG. 3;

FIG. 17 is an enlarged partial view of portion 17 in FIG. 3;

FIG. 18 is an enlarged partial view of portion 18 in FIG. 3;

FIG. 19 is an enlarged partial view of portion 19 in FIG. 4;

FIG. 20 is an enlarged partial view of portion 20 in FIG. 4;

FIG. 21 is an enlarged partial view of portion 21 in FIG. 5;

FIG. 22 is an enlarged partial view of portion 22 in FIG. 5;

FIG. 23 is an enlarged partial view of portion 23 in FIG. 5;

FIG. 24 is an enlarged partial view of portion 24 in FIG. 6;

FIG. 25 is an enlarged partial view of portion 25 in FIG. 6;

and,

FIG. 26 is an enlarged partial view of portion 26 in FIG. 6.

The dash-dot-dash lines define the boundaries of the enlarged views of the pet hair lint remover and form no part of the claimed design. The evenly spaced broken lines illustrate portions of the pet hair lint remover that form no part of the claimed design.
